UNITED STATES PATENT OFFICE

117,874

DESIGN FOR A STERILIZING TUBE REFLECTING UNIT

Donald P. Caverly, Marblehead, Mass., assignor
to Hygrade Sylvania Corporation, Salem, Mass.,
a corporation of Massachusetts

Application December 22, 1938, Serial No. 81,937

Term of patent 7 years

To all whom it may concern:

Be it known that I, Donald P. Caverly, a citizen of the United States, residing at Marblehead, in the county of Essex and State of Massachusetts, have invented a new, original, and ornamental Design for a Sterilizing Tube Reflecting Unit, of which the following is a specification, reference being had to the accompanying drawing, forming part thereof.

The figure is a perspective view of a sterilizing tube reflecting unit, showing my new design. The other side of the device of my design is substantially the same as shown in the drawing.

I claim:

The ornamental design for a sterilizing tube reflecting unit, as shown and described.

DONALD P. CAVERLY.
